UNITED STATES PATENT OFFICE.

RICHARD DIGGLE HAWORTH, OF WELLINGTON, NEW ZEALAND.

MANUFACTURE OF CARDBOARD BOXES.

No. 884,384.

Specification of Letters Patent.

Patented April 14, 1908.

Application filed October 27, 1906. Serial No. 340,859.

To all whom it may concern:

Be it known that I, RICHARD DIGGLE HAWORTH, a subject of His Majesty the King of Great Britain and Ireland, residing at Wellington, in the Provincial District of Wellington, in the Colony of New Zealand, have invented certain new and useful Improvements in and Relating to the Manufacture of Cardboard Boxes, of which the following is a specification.

This invention relates to cardboard boxes especially those known as collapsible.

The object of the invention is to provide an improved fastening for the ends and sides. According hereto the card forming the end of a box is bent at right angles at each end, each part terminating in a hook shaped portion which is passed through a slot cut in the end of the side of the box.

The hook is engaged by a turn button which is pivoted by an eyelet, rivet or the like upon the inside of the box.

My invention is illustrated in the accompanying drawing wherein:—

Figure 1 is a plan view of a box collapsed. Fig. 2 is a part sectional side elevation showing the end and side connected together. Fig. 3 is a sectional elevation on 3—3, Fig. 2.

Referring first to Fig. 1.—The card from which the box is made has the part 1 which forms the bottom, the parts 2 and 3 forming the sides and the parts 4 and 5 forming the ends. The card is scored as shown in dotted lines to facilitate folding and all the parts are bent upwardly at right angles to the bottom. Each of the parts 4 and 5 has at each

end a portion 6 which is cut out, by a die or the like to form a hook 7. Each of the ends of the side pieces 2 and 3 has a slot 8 through which is passed one of the opposing hooks of the end portion as clearly shown in Fig. 2.

Buttons 9, one for each of the hooks, are pivotally secured each by an eyelet 10 to one of the side pieces in such manner that it can be turned down into the position shown in dotted lines Fig 2 to allow its hook to be passed over it and then turned round upon its pivot as shown in full lines in the same figure to secure the hook.

A washer 11 of material of approximately the thickness of the material from which the hook is formed, is threaded upon an eyelet between the button and the side of the box to facilitate the turning of the button.

What I do claim and desire to secure by Letters Patent of the United States is:—

A collapsible box comprising a bottom, foldable sides and ends integral with the bottom, slotted hooks integral with the extremities of the ends and adapted to pass through slots in the sides, and buttons pivoted to the sides and adapted to pass through the slots of, and retain the hooks, substantially as set forth.

In testimony whereof I have signed my name to this specification in the presence of two witnesses.

RICHARD DIGGLE HAWORTH.
